UNITED STATES PATENT OFFICE.

CHARLES H. JOCKMUS, OF ANSONIA, CONNECTICUT.

ELECTRIC SWITCH.

Application filed October 11, 1923. Serial No. 667,791.

This invention relates to pull chain switches of the type particularly adapted to be used in connection with electric lamp sockets.

Heretofore, considerable difficulty has been experienced with pull chain switches of the type to which my invention pertains in that excessive arcing has been caused between the stationary and movable contacts upon movement of the movable contact out of electrical engagement with the stationary contact.

An important object of my invention is to provide in a device of the character mentioned, a means whereby such arcing is eliminated thus prolonging the life of the contact elements by reason of the fact that the objectionable burning out or fusing of the same is thereby overcome.

Other objects and certain advantages of the invention will become apparent from the following description when taken in connection with the accompanying drawings in which

Figure 1 is a plan view of a switch embodying my invention.

Figure 2 is an elevation of the switch mechanism shown in Figure 1.

Figure 3 is a sectional view taken on the line 3—3 of Figure 1.

Figure 4 is a view similar to that of Figure 3, showing however, a slightly modified form of the invention.

In the drawings, wherein for the purpose of illustration is shown what I at present consider the preferred forms of my invention, the numeral 5 indicates a base formed of a nonconducting material, such as porcelain or the like, to which is connected a central contact 6 adapted to engage the central contact of an electric lamp, not shown, when the switch mechanism is embodied in an electric lamp socket. The central contact 6 is connected by means of a screw 7 to a bearing 8 upon which is mounted to oscillate a movable contact or switch arm 9 having a wiper arm 10 adapted to be moved under and into engagement with a stationary contact 11, the forward end of which is turned slightly upward, as shown at 12, in order to facilitate entrance of the wiper arm 10, as will be readily appreciated. The movable contact

9 pivotally mounted upon the bearing 8 is rigidly connected to a block 12' of insulating material carrying a shaft 13 which is journaled at its upper end to a horizontal ledge 14 forming a part of a frame 15 with which the switch-operating-mechanism 16 is associated. The operating mechanism 16 is adapted to be actuated by means of the conventional form of pull chain 17 to effect an intermittent oscillatory movement of the wiper arm 10 into and out of engagement with the stationary contact 11. The stationary contact 11 is, by means of a screw 18, connected to a bracket 19 provided with a screw 20 adapted to function as a means for connecting an electric conductor, not shown, to the bracket 19. It will be appreciated, therefore, that when the switch arm 9 is maintained in its full line position, as shown in the drawings, electrical communication is established between the central contact 6 and the bracket 19, which communication is severed the instant the contact 9 is moved to its dotted line position shown in Figure 1.

In order to smother or eliminate the heretofore objectionable arcing upon movement of the wiper arm 10 out of engagement with the stationary contact 11, I have provided the latter with a cup-shaped depression or pocket 21 within which is adapted to be placed a quantity of nonconducting oil or grease 22. The grease functions not only as a lubricant for preventing excessive wear between the movable contact 9 and stationary contact 11, but also serves to smother or extinguish the arc incident to moving the wiper arm 10 out of engagement with the contact 11. In order to further insure elimination or extinguishing of the arc, I have provided a snuffer 23 which is superimposed upon the stationary contact 11 and provided with an opening 24 adapted for the reception of the depression or pocket 21, shown most clearly in Figure 3. This snuffer is in the form of a relatively small piece or strip of insulating material, such as fibre, bakelite or the like, and is held in position intermediate the contact 11 and the bracket 19 by means of the screw 18.

By reason of the presence of the grease 22, the retention of which is made possible

2
by the depression or cup-shaped member 21, and by reason of the provision of the snuffer 23, I have succeeded in eliminating the objectionable arcing heretofore experienced in switches, of the type shown, upon breaking the circuit incident to moving the wiper arm 10 out of electrical engagement with the stationary contact 11. By so eliminating the objectionable arcing, the life of the switch is necessarily prolonged due to the fact that the burning out or fusing of the contact elements 9 and 11 has been obviated.

Referring to Figure 4, it will be noted that the snuffer 23' is in the form of a solid piece of material, such as fiber or the like, and is mounted upon and adapted to move with the wiper arm 10, the snuffer being secured to the arm by any suitable means, such as rivets or the like, not shown. It will be observed, too, in the case of the modified form of my invention, that as a stationary contact the base 19' of the bracket 19 may be employed, the base being cut away or relieved, as shown at 20', in order that the wiper arm 10 may ride freely into position upon the upper face of the base when the operating mechanism 16 is so actuated as to close the circuit. The nonconducting oil or grease 22 in the case of the modification shown in Figure 4, instead of being confined within a suitable pocket, such as that hereinbefore described, may be distributed over the base 19' at the curved or relieved end thereof, as shown, in which case it is held in place by cohesion as will be readily appreciated.

While I have shown and described what I at present consider the preferred forms of my invention, it is to be understood that minor changes as to the details of construction may vary without departing from the spirit of the invention or the scope of the subjoined claims.

I claim:

1. An electric switch comprising relatively movable contact elements one of which is provided with a pocket adapted for the reception of a lubricant adapted to function as an arc extinguishing medium upon formation of an arc between said contact members when they are moved relatively with respect to each other, and a snuffer associated with one of said contact elements and adapted to co-operate with said grease to extinguish the arc formed between said contact elements upon relative movement therebetween.

2. An electric switch comprising contact elements adapted to be moved into and out of engagement with each other, one of said contacts being provided with a pocket, an arc extinguishing medium carried within said pocket and snuffer means associated with one of said elements and adapted to co-operate with said arc extinguishing medi-

um for further insuring extinguishing of the arc upon relative movement between said contact elements.

3. An electric switch comprising contact elements adapted to be moved into and out of engagement with each other, one of said contacts being provided with a pocket, an arc extinguishing medium carried within said pocket, snuffer means associated with one of said elements and adapted to co-operate with said arc extinguishing medium for further insuring extinguishing of the arc upon relative movement between said contact elements, said means being in the form of a strip of insulating material overlying said pocket.

4. An electric switch comprising a base, a contact member having a pocket mounted on said base, a strip of insulating material superimposed on said pocket member, and a second contact member adapted to be moved into and out of contact with said first contact member.

5. An electric switch comprising a stationary contact member having a pocket, an arc extinguishing medium carried within said pocket, an insulating strip adjacent to said stationary contact, and a movable contact adapted to be moved into and out of engagement with said stationary contact.

6. An electric switch comprising a stationary contact, a movable contact adapted to be moved into and out of engagement with said stationary contact, means associated with said stationary contact for retaining an arc-extinguishing medium, and an insulating member adjacent and overlapping said stationary contact member for further extinguishing the arc upon relative movement between said contact elements.

7. An electric switch comprising a relatively fixed contact element, a relatively movable contact element, and means to hold a lubricant adjacent said fixed element and in position where the body of the lubricant will come into direct contact with said movable element when said movable element is brought into contact with said fixed element.

8. A switch comprising a base, a relatively fixed contact element mounted on said base, a relatively movable contact element cooperating with said fixed element and adapted to pass between said base and said fixed element, and a lubricant disposed between said base and said fixed element and adapted to contact with said movable element when said movable element is brought into position between said base and said fixed element.

9. An electric switch comprising two relatively movable contact elements, one of said elements having a pocket holding a lubricant in position where the body of the lubricant

will come into direct contact with the other of said elements during said relative movement.

10. A switch comprising a base, a relatively fixed contact element mounted on said base and having a pocket therein opening toward said base, a relatively movable contact element cooperating with said fixed element and adapted to pass between said

base and said fixed element, and a lubricant 10 disposed in said pocket and adapted to contact with said movable element when said movable element is brought into position between said base and said fixed element.

In testimony whereof, I have affixed my 15 signature to this specification.

CHARLES H. JOCKMUS.
